PAGE 2

Fig. 2.

Fig. 5.

Fig. 3.

Fig. 4.

FIG. 1 is an isometric view of a data encoding unit, showing our new design;

FIG. 2 is a top plan view thereof;

FIG. 3 is a side elevation thereof;

FIG. 4 is a bottom plan view thereof;

FIG. 5 is a rear elevational view thereof.

The undisclosed side portions of the unit are substantially the same in appearance as the side shown.

We claim:

The ornamental design for a data encoding unit, as shown and described.
